UNITED STATES PATENT OFFICE.

STANLEY A. FROLKING, OF CLEVELAND, OHIO, ASSIGNOR TO BRILLIANT GLASS PRODUCTS, INC., OF BRILLIANT, OHIO, A CORPORATION OF OHIO.

DESIGN FOR A BATHROOM FIXTURE.

Application filed January 26, 1927. Serial No. 20,490. Term of patent 7 years.

To all whom it may concern:

Be it known that I, STANLEY A. FROLKING, a citizen of the United States, residing at Cleveland, in the county of Cuyahoga and State of Ohio, have invented a new, original, and ornamental Design for Bathroom Fixtures, of which the following is a specification, reference being had to the accompanying drawing, forming a part thereof.

In the drawing, Fig. 1 is a front view; Fig. 2 is a side view; Fig. 3 is a bottom view; and Fig. 4 is a top view showing my new design.

I claim:

The ornamental design for a bathroom fixture substantially as shown.

STANLEY A. FROLKING.
